UNITED STATES PATENT OFFICE.

CALVIN B. PATCH, OF GLENELLYN, ILLINOIS, ASSIGNOR TO WILLIAM H. MINER, OF CHAZY, NEW YORK.

SIDE BEARING FOR RAILWAY-CARS.

1,230,210.

Specification of Letters Patent. Patented June 19, 1917.

Application filed July 15, 1916. Serial No. 109,444.

To all whom it may concern:

Be it known that I, CALVIN B. PATCH, a citizen of the United States, residing at Glenellyn, in the county of DuPage and State of Illinois, have invented a certain new and useful Improvement in Side Bearings for Railway-Cars, of which the following is a full, clear, concise, and exact description, reference being had to the accompanying drawings, forming a part of this specification.

This invention relates to improvements in side bearing for railway cars.

One object of the invention is to provide a simple, relatively cheap roller side bearing for railway cars and so arranged that the roller will be automatically returned to central or normal position after each actuation.

In the drawing forming a part of this specification, Figure 1 is an end elevation of portions of a body and truck bolster of a car, showing my improvements in connection therewith. Fig. 2 is an enlarged longitudinal sectional view taken substantially on the line 2—2 of Fig. 1. Fig. 3 is a transverse, vertical sectional view taken on the line 3—3 of Fig. 2. And Fig. 4 is a view corresponding to a portion of Fig. 2 illustrating slight modification of the means for attaching the springs to the roller. Figs. 5, 6 and 7 are views corresponding respectively with Figs. 1, 2 and 3, but illustrating a still further embodiment of the invention, Fig. 6 being taken on the line 6—6 of Fig. 5 and Fig. 7 being taken on the line 7—7 of Fig. 6.

Referring now to the construction illustrated in Figs. 1, 2 and 3, 10 denotes the body bolster, 11 the truck bolster pivotally connected at their centers in the usual manner and A the improved side bearing preferably mounted on the truck bolster. As shown, the side bearing A preferably comprises a retaining member or base casting B having flanges 12—12 by which it is riveted or otherwise secured to the truck bolster. The base casting B is of substantially hollow box-like form having side walls 13—13 and curved end walls 14—14. On its interior, the base casting B is provided with a steel insert 15 forming a tread or bearing surface for the anti-friction roller. As shown, the anti-friction roller 55 comprises two members C and C¹ spaced

apart by means of a connecting journal or axle 16 having an enlarged central portion forming flanges as indicated at 17—17, the small ends of said journal or axle being inserted in central recesses 18—18 in the 60 roller members C and C¹. By this means, the members C and C¹ are moved in unison and retained in proper spaced relation. The centrally enlarged portion of the axle member 16 is provided on opposite sides 65 thereof with eyes 19 to which are attached the inner ends of springs 20—20, the opposite ends of said springs being secured to eye bolts 21—21 detachably mounted in the end walls 14 of the base casting. From 70 the foregoing description, it is apparent that the roller will be returned to normal position by the springs after each actuation thereof and by adjusting the eye bolts 21, the tension of the springs 20 may be ad- 75 justed as desired.

In the modification shown in Fig. 4, the two spaced sections of the roller are formed integrally and connected by an integral central portion 116. To form suitable means 80 of connecting this central portion with the centering springs, I provide a collar formed in two parts 117—117, each having perforated ears 118—118 at their ends through which are hooked the inner ends of the 85 springs 120.

In the modification illustrated in Figs. 5, 6 and 7, the base casting and roller members are the same as those illustrated in the other views. In this construction, however, 90 the journal or axle member 216, which connects the roller section C and C¹ is preferably of I beam cross section at the center as indicated at 217 in Fig. 6. The vertical web of this section is centrally perforated 95 as indicated at 218 to permit the passage therethrough of a long bolt 219. The bolt 219 is extended through suitable perforations 219—219 in the end walls of the base casting and is held in position by a nut 220. 100 Springs 221 are mounted on said bolt on opposite sides of the roller so that as the roller is moved from normal position, one of said springs will be compressed and upon release of the pressure on the roller, will 105 automatically return the latter to central position.

I have herein shown and described what I now consider the preferred means of carrying out my invention, but it will be under- 110

stood that the same is merely illustrative and that various changes and modifications may be made in the parts without departing from the spirit of the invention.

I claim:

5. 1. In a roller side bearing, the combination with a base casting, of a pair of spaced roller members within said base casting and movable in unison, springs on each side of said roller members, a central axle member extending between the roller members, said springs extending to said axle member and into the space between the roller members.
10. 2. In a roller side bearing, the combination with a base casting, of a pair of spaced roller members, a journal extending between said roller members to thereby move the same in unison, and springs extending between the base casting and said journal, the inner ends of said springs being located between the said roller members.
15. 3. In a roller side bearing, the combination with a base casting, of a pair of spaced roller members, a journal extending between said roller members to thereby move the same in unison, and springs extending between the base casting and said journal, the inner ends of said springs being located between the said roller members, the journal being detachably connected with the roller members.
20. 4. In a roller side bearing, the combination with a hollow base casting, of two

roller members mounted within said base casting, a journal extending between and connecting said roller members, and springs on opposite sides of said journal, said springs being attached at their inner ends to the journal and at their outer ends to the base casting.

35. 5. In a roller side bearing, the combination with a hollow base casting, of two roller members mounted within said base casting, a journal extending between and connecting said roller members, and springs on opposite sides of said journal, said springs being attached at their inner ends to the journal and at their outer ends to the base casting, and means for adjusting the tension of said springs.

40. 6. In a roller side bearing, the combination with a base casting, of a pair of spaced roller members within said base casting and movable in unison, a central axle member extending between the roller members, and spring means connected to said axle member and the casting, said spring means extending into the space between the roller members.

45. In witness that I claim the foregoing I have hereunto subscribed my name this 13th day of July, 1916.

CALVIN B. PATCH.
